United States Patent Office

Des. 185,038
Patented Apr. 28, 1959

185,038

TOWEL CABINET

Frederic P. Plotkin and Philip Shore, Los Angeles, Calif.

Application October 17, 1958, Serial No. 53,025

Term of patent 14 years

(Cl. D4—3)

Fig. 1 is a perspective view of a towel cabinet, showing our new design;

Fig. 2 is a top or plan view of the front thereof;

Fig. 3 is a front elevational view;

Fig. 4 is a bottom plan view; and

Fig. 5 is a side elevational view thereof.

Figs. 2 through 5 are shown on enlarged scales.

The dominant features of the design reside in the portions shown in full lines.

We claim:

The ornamental design for a towel cabinet, as shown and described.
